United States Patent Office

Des. 185,610
Patented June 30, 1959

185,610

PORTABLE TOILET UNIT

Richard E. Nearman, Rockville, Md., assignor to Washington Technological Associates, Inc.

Application April 25, 1958, Serial No. 50,627

Term of patent 14 years

(Cl. D4—2)

FIG. 1

Des. 185,610

PAGE 2

FIG. 2

FIG. 3

FIG. 4

Fig. 1 is a perspective view of the new portable toilet unit as it would appear from a point off to one side;

Fig. 2 is a perspective view similar to Fig. 1 but showing the new portable toilet unit as it would appear from a point off to the opposite side;

Fig. 3 is a side elevation of the new portable toilet unit; and

Fig. 4 is a rear view of the new portable toilet unit. I claim:

The ornamental design for a portable toilet unit, substantially as shown.
